FLOOR TREATING MACHINE

Raymond Descarries, Montreal, Quebec, Edouard Gaudry,
Cite St. Laurent, Quebec, and Paul E. Gaudry, Laval
des Rapides, Quebec, Canada, assignors to Electrolux
Corporation, Old Greenwich, Conn., a corporation of
Delaware

Filed May 9, 1967, Ser. No. 7,032

Term of patent 14 years

(Cl. D37—3)

Fig. 4

Fig. 5

Fig. 6

FIG. 1 is a perspective view of a floor treating machine showing our new design.

FIG. 2 is a side view thereof showing the left side of the machine as viewed in FIG. 1.

FIG. 3 is a rear elevation thereof.

FIG. 4 is a rear view thereof with the handle shown in a non-operating position.

FIG. 5 is a side elevation thereof as seen in FIG. 4.

FIG. 6 is a front view thereof as seen in FIGS. 4 and 5.

The broken line showing of the electric cord plug is for illustrative purposes only.

We claim:

The ornamental design for a floor treating machine, as shown and described.
